(57) **CLAIM**

The ornamental design for a multi-sided core guard, as shown and described.

DESCRIPTION

FIG. 1 is a front view illustrating my design for a multi-sided core guard;

FIG. 2 is a right side view thereof;

FIG. 3 is a top view thereof;

FIG. 4 is a left side view thereof;

FIG. 5 is a bottom view thereof;

FIG. 6 is a rear view thereof;

FIG. 7 is a rear perspective view thereof; and,

FIG. 8 is a front perspective view thereof.

The broken lines in the drawings are for illustrative purposes only and form no part of the claimed design.
